Jr. William Eason - C. M.

UNITED STATES PATENT OFFICE.

AMOS HOLBROOK, OF LYNN, MASSACHUSETTS.

IMPROVEMENT IN FIRE-ALARM TELEGRAPHS.

Specification forming part of Letters Patent No. 153,958, dated August 11, 1874; application filed December 3, 1873.

To all whom it may concern:

Be it known that I, AMOS HOLBROOK, of Lynn, in the county of Essex and State of Massachusetts, have invented a certain new and useful Signal-Indicator for Fire-Alarms, of which the following is a specification:

My invention relates to a device by which I cause two or more pointers and dials to indicate the number of the district which is being struck by the electric fire-alarm.

The nature of my invention consists in combining with the device through which the motion of the pointers is governed a timer, said timer being so arranged that when a signal is received, which starts the pointer, it starts an incline, which, operating through levers, will, in a certain number of seconds, throw a detent-tripper out of connection with the detent of the first dial, and into connection with the detent of the second dial; then continued motion of the timer will throw the detent-tripper out of connection with either detent, so that, though the signal be received by the device at the next round—that is, after an interval of twenty seconds—there will be no further movement of the pointers on the dials, as their let-off detents are no longer acted upon.

Figure 1 is an elevation of my device. Fig. 2 is a horizontal section through a part of the same. Fig. 3 is a vertical section taken on the line *x y* of Fig. 1.

Let *A* represent the base or frame, to which I attach the other parts of my invention. *D*¹ is a notched wheel, upon the axle of which I attach a pointer, *D*². This pointer moves over the face of the dial. (Not shown in the drawings.) The notches in the wheel *D*¹ are arranged as shown, so that if the lever *D* is depressed the wheel will be free to revolve. The lever *D*, when depressed by the action of the magnet, which will be hereafter explained, returns quickly to place, so that the dial-wheel *D*¹ can only move one notch, of course carrying the pointer *D*² but one division of the dial. The dial-wheel *E*¹, pointer *E*², and lever *E* are arranged similarly to the device *D*¹ *D*² *D*, already described. Motion is given to the dial-wheels by the weights *D*³ *E*³. Each of the dial-wheels is also provided with a retarding device, which serves to prevent a too quick motion when released. *B* is a rod, which is

actuated by an electro-magnet, through which a current is passed at the instant a signal is given. This rod *B* connects with the bent lever *B*¹, which is pivoted at *B*². The upper end of this bent lever passes between two starts, *C*¹ *C*, which project from the quill *C*⁴. From this quill *C*⁴ a bent arm, *C*³, Figs. 1 and 2, projects, the end of it extending so as to reach to the ends of the levers *D* and *E*, which are bent, as shown at *d* and *e*. This quill *C*⁴ is free to rock and slide on the stud *C*², but is held in position by the spring *C*⁵, Fig. 2. *L* is a gear-wheel operated by a clock-movement, regulated so as to give it a fixed velocity. *N*' is the regulator fly-wheel, and held from revolving by the hook *N*, which is connected, by the rod *M*, to the lever *B*¹, as shown. *M*¹ is a latch connected to the hook *N*, so as to swing with it about the center *n*. *M*² is a spring, which presses against the latch *M*¹. *M*³ is a second latch, pressed up by a spring, *M*⁴. This latch moves up and holds the latch *M*¹ and the hook *N* when the same have been drawn back by the rod *M*. *F*⁷ is a segment-gear, hung at *F*² to the swinging arm *F*¹, which is pivoted on *F*³. This segment-gear *F*⁷ is hung, as described, on a swinging arm, so that it may be forced out of connection with the wheel *L*. This is effected by means of the link *B*³, which is attached to the bent lever *B*¹, so that whenever *B*¹ is pulled back the segment-gear *F*⁷ is freed from the wheel *L*, and drops until stopped by the gage-screw *P*. *K*' is an incline, against which the pin *K* contacts whenever the segment-gear *F*⁷ is raised high enough. The action of this incline on the pin *K* forces the segment-gear *F*⁷ back out of contact with the gear *L*, so that, though *L* continues to revolve, it cannot raise *F*⁷ any higher. *F*⁸ is a spring, acting against the swing *F*¹, and serves to push the segment-gear *F*⁷ toward the gear *L*. *F*⁶, Figs. 1 and 3, is an incline, attached to the segment-gear *F*⁷, and arranged as shown in Fig. 3, so as to act, through the lever *F*⁴, upon the thimble *C*⁴, and through it upon the arm *C*³, Fig. 1. Inspection of Fig. 3 will show that, as the segment-gear *F*⁷ rises, it will carry up the incline *F*⁶, which, acting upon the lever *F*⁴, carries back the sleeve *C*⁴ and arm *C*³. As the movement of this incline *F*⁶ is timed by clock-

work, it is evident that the movement of the sleeve C^4 and arm C^3 will also be timed, so that, if F^7 be allowed to rise a certain number of seconds, the arm C^3 will begin to move over the bent part d , Fig. 2, of the let-off lever D . If more time is allowed, the arm C will extend over the part e of the let-off lever E . If still more time is allowed, the arm C^3 will pass beyond e onto the rest Q . H is a drop-lever, arranged so that the spring H^3 will press against the sleeve C^4 , as shown in Fig. 3. As soon as the sleeve C^4 is pressed in, so that its arm C^3 has passed beyond d , Fig. 2, the lever H will drop below the shoulder C^5 , Fig. 3, of the sleeve C^4 , and thus prevent it from springing back when released from the lever F^4 . As soon as this sleeve C^4 has passed beyond e , Fig. 2, then H will drop over the end of the sleeve C^4 , and prevent it from coming back when released.

The operation of my device is as follows: The weights $L^1 D^3 E^3$ are wound up, the hook N engaging with the fly N^1 , so as to prevent the movement of the clock-work. The segment F^7 is allowed to drop to its lowest point, as shown in Fig. 1; the lever H is raised, as shown in Fig. 1, so as to allow the sleeve C^4 to take the position represented in Fig. 2, so that its arm C^3 rests over the bent part d of the let-off lever D . Now, when a signal is received, the magnet, acting on the wire B , draws back the lever B^1 , and, acting through C^1 , the sleeve C^4 , and arm C^3 , depresses the let-off lever D ; this allows the dial-wheel D^1 to revolve one notch, so that the hand D^2 will point to I on the first dial. At the same time this is going on, the rod M releases the clock-work, and the segment F^7 begins to ascend, carrying with it the incline F^6 , which, acting through the lever F^4 , pushes the arm C^3 toward E , Fig. 2. If this motion is only allowed to continue for two or three seconds, then the next stroke of the signal will again act, as before, on the le-

ver D , and the first dial-hand D^2 will point to figure 2 of the dial. Now, if an interval of six or seven seconds be allowed, as would be in case the alarm came from box twenty odd, then the arm C^3 will have passed over to the bent end e of the lever E . In the meantime the lever H will drop in front of the shoulder C^5 , Fig. 3, and prevent the sleeve C^4 from springing back, and carrying the arm C^3 over D again; then the next stroke of the signal will be recorded by the pointer E^2 of the second dial, and the number will be read as 21; or, if another stroke is given within two or three seconds, the pointer E will go to figure 2 of the second dial, and the record will be 22. If this is the true number no other stroke will be given for about twenty seconds, in which time the action of the clock-work through F^6 , F^4 , and C^4 , will carry the arm C^3 beyond E , Fig. 2, over the rest Q , and in the meantime the lever H will have dropped down in front of the sleeve C^4 , so it cannot slip back, and the stroke given in repeating the signal will have no effect upon either dial, as the arm C^3 will touch neither the levers D or E .

I claim as my invention—

1. The combination of signal-indicating dials and the detent let-off device $C^3 C^4 C^2$ with the lever F^4 , incline F^6 , and segment-gear F^7 , operating substantially as described, and for the purpose set forth.

2. The combination of the segment-gear F^7 and incline F^6 with the sleeve C^4 and arm C^3 , operating substantially as described, and for the purpose set forth.

3. The combination of the lever H with the sleeve C^4 , operating substantially as described, and for the purpose set forth.

AMOS HOLBROOK.
